NAPKIN DISPENSER

Earl N. Borden, Hillsboro, Tex.

Application March 19, 1948, Serial No. 15,790

1 Claim. (Cl. 312—62)

1

This invention relates to dispensers for napkins and similar articles which are intended to be removed from a holder one at a time.

One of the objects of the invention is to provide a dispenser comprising a casing which serves as a holder for a pack or charge of laminated sheets or napkins, and having therein a spring unit having a capacity to push the sheets or napkins toward the discharge opening by engaging the rear of the pack or charge near the top and bottom thereof so as to exert a more or less uniform outward pressure thereon.

Another object of the invention is to provide a follower unit in the form of an arched or inverted V-shaped member wherein the arms or leaves of said member have the characteristic of a spring which may be compressed when the pack or charge is inserted in the housing of the device and which exerts continuing pressure on the charge until it is fully dispensed. In that connection, the invention contemplates providing the arm or leaf of the follower unit with an integral struck out spring finger which assists in pushing the pack or charge of napkins toward the dispensing opening.

A further object is to provide a napkin dispenser consisting of a minimum number of parts, namely, a casing having opposite side-walls provided with openings and a single or one piece follower unit of inverted V, or equivalent, shaped form, having fingers struck from the leaves thereof and adapted to be held in the housing or casing by a third element, namely, a bottom plate or base. Thus, basically, the invention proceeds from the practical consideration of providing a commercially practical and feasible follower device which consists of a minimum number of parts, and which lends itself to standard manufacturing practices, thereby to provide a construction which may be economically produced.

A preferred and practical embodiment of the invention is shown in the accompanying drawings, in which:

Figure 1 is an exploded perspective view, illustrating the several parts of the invention.

Figure 2 is a vertical cross sectional view of the device, loaded with sheets or napkins for use.

Similar reference characters designate corresponding parts throughout the several figures of the drawings.

As will be observed from Figure 1, the assembly generally includes a cover or casing A, a spring follower unit B, and a bottom or base C. The casing A is provided with end walls 1 and

2 side-walls 2, the latter having the openings 3. The cover is preferably formed with its upper end closed in any appropriate fashion, while its bottom end is open, thereby to receive the inverted V-shaped follower unit B. After the unit B is placed in position, the base or bottom C may be placed in the open end of the cover and affixed thereto by welding, riveting, punching or any well-known means of fastening the base to the open end of the casing, depending on whether the housing and its several parts are made of metal or plastic. Thus, it will be seen that the parts A, B and C may be readily made by standard manufacturing practices and assembled by merely placing the unit B in the cover A and then affixing the bottom or base C.

Referring to the follower unit B, it will be observed that the same is preferably of inverted V-shaped formation, thereby to provide the arms or leaves 4. Said leaves 4 preferably have their lower ends angularly disposed outwardly, as indicated at 5. Also, each leaf 4 has a spring finger 6 struck out therefrom. This finger is preferably integrally connected with the lower portion of a leaf at the zone of the junction of the angular portion 5 with the main leaf, and extends upwardly and outwardly from the body of the leaf in its unsprung condition. The upper end of each finger 6 is preferably angularly disposed, as indicated at 7. The lower portion 5 of the leaves 4 and the upper portions 7 of the fingers 6 are intended respectively to engage the upper and lower portions of the pack or charge of napkins N, as will be seen from Figure 2. It will also be observed from this figure that when the arms or leaves 4 of the unit B are compressed, the intermediate portions of the fingers 6 will engage the intermediate parts of the pack of napkins N.

To assist in properly positioning the unit B in the cover or casing A, the apical portion 8 thereof is preferably anchored to the upper, inner portion of the casing A by inwardly projecting studs or spaced lugs 9. These lugs may be of any appropriate form, either integral or separate, depending on whether the casing A is made of plastic or metal. The purpose of the opposite pairs of spaced lugs 9—9 is to slidably anchor the apical portion of the unit B in the cover and prevent lateral shifting thereof. Clearly, it is within the scope of the invention to make the lugs 9 in the form of spaced extrusions of the end walls 1. It will, therefore, be seen that the opposite pairs of spaced lugs not only assure the centering of the unit B when it is assembled rela-

tive to the cover, but also assure proper functioning of the unit B when it is in use to the extent that the opposite spring leaves 4-4 and the spring fingers 6-6 will exert uniform pressure on the charge or pack of napkins in the cover.

The base C may be provided with an abutment 11 to prevent the lower end of either leaf of the unit B from being moved too far toward the other if usual hand pressure is exerted on one stack of napkins while the other is partially reduced in volume.

When the device is assembled as shown in Figure 2, it will be seen that the charge or pack of napkins N may be placed in the cover by pushing the same through the openings 3-3, thereby compressing the opposite spring leaves 4-4, as well as the fingers 6-6. As the volume of the charge or pack of napkins N becomes reduced by removing the exposed napkins, the leaves 4-4 and fingers 6-6 will tend to expand to the position shown in Figure 1 until the dispenser is empty. The dispenser may then be refilled for use.

From the foregoing, it is believed that it will be understood that the construction and arrangement described provides a simple and practical form of sheet dispenser that may be readily made of metal or plastic parts, and which, in use, functions efficiently for the intended purpose.

As shown in Figure 1, the end wall 1 of the

casing may be provided with cooperating guide members 10 on the side and bottom edges of the casing for receiving a menu or other card.

I claim:

5 A napkin dispenser, including, a cover having opposite side-walls, each provided with an opening, a bottom wall, an inverted V-shaped follower unit including opposite spring leaves and angularly disposed spring fingers struck out from the body of said leaves, the bottom of said leaves and the upper portions of the fingers serving to engage upper and lower portions of napkins confined between one side of the unit and the inner side of the related opening in the cover, and pairs of spaced studs projecting inwardly from the upper portion of the casing to slidably receive the apex of said unit and anchor the upper portion thereof in the cover.

EARL N. BORDEN.
